Patented Sept. 15, 1925.

UNITED STATES PATENT OFFICE.

LUCIUS E. WEAVER, OF EAST HAMPTON, CONNECTICUT, ASSIGNOR TO SUMMIT THREAD COMPANY, OF EAST HAMPTON, CONNECTICUT, A CORPORATION OF MAINE.

SEWING-MACHINE SHUTTLE.

Application filed June 16, 1924. Serial No. 720,230.

To all whom it may concern:

Be it known that I, LUCIUS E. WEAVER, a citizen of the United States, residing at East Hampton, in the county of Middlesex and 5 State of Connecticut, have invented new and useful Improvements in Sewing-Machine Shuttles, of which the following is a specification.

This invention relates to a shuttle comprising a head forming one end of a bobbin-receiving cavity, a central post in said cavity on which a bobbin in the cavity is rotated, and a thrust support at the opposite end of the cavity.

10 A bobbin usually of the ready-wound variety, is enclosed in the cavity with its inner end spaced from the head.

A shuttle embodying the invention is characterized by the improved adjunct, 20 hereinafter described and claimed, for preventing undesirably free rotation of the bobbin, and for partly ejecting the same, or a cap tube forming a component part thereof, from the cavity.

25 Of the accompanying drawings forming a part of this specification,—

Figure 1 is a side view of a shuttle body to which my improved adjunct is applicable.

Figure 2 is a section on line 2—2 of Figure 1.

Figure 3 is an enlarged sectional view showing the bobbin case separated from the shuttle body.

Figure 4 is a side view and Figure 5 an 35 edge view of the bobbin-controlling adjunct of my invention shown by Figures 1, 2 and 3, this being the preferred form.

Figure 6 is a perspective view showing 40 another form of the bobbin-controlling adjunct.

In the drawings, 12 designates a shuttle body, which may be of any suitable form, and is provided with a bearing post 13, and with a bobbin receiving cavity through 45 which said post extends. In this instance the cavity is formed in a bobbin case. A portion 12^a of the body constitutes an end thrust bearing for the outer end of a bobbin.

50 The bobbin case is composed, as usual, of an annular wall or curb 14, open at one end and closed at the opposite end by a head 15, supporting and surrounding the inner end of a central tubular post 16, which is formed 55 to receive the body post 13, the head usually

including a facing disk 15^a forming the inner side of the head. The head and the body post may be provided with any suitable means, adapted to releasably confine the bobbin case on the inner post. Said 60 means may include a sliding latch 17, shown in section, adapted to engage a groove 18, in the body post, the latter projecting through an opening in the head, the latch 65 springing as usual, into the groove, to confine the case, and being displaceable to release the case.

The tubular post 16 is provided, as heretofore, with a split resilient stop sleeve 30 adapted to yieldingly embrace the post and 70 be secured thereto by friction. The inner end of the stop sleeve is adapted to arrest a friction disk 31 and prevent the removal of the friction disk from the bobbin case when the bobbin is withdrawn, the disk bearing 75 on the inner end of the bobbin.

The bobbin may comprise a core or cap tube 19, usually of paper, and a winding 20 of thread universally wound on the tube.

It is customary to interpose between the 80 head 15 and the friction disk 31 a resilient bobbin-controlling adjunct in the form of a spring yieldingly opposing the rotation of the bobbin, said spring bearing frictionally on the head and on the disk, and exerting 85 pressure on the bobbin, through the disk, to press the outer end of the bobbin against the end thrust bearing 12^a.

In carrying out my invention I provide an 90 improved adjunct which is superior to any heretofore used, so far as I am aware, and is characterized as next described.

Said adjunct includes a floating hub portion adapted to bear and rotate on the tubular post 16, and resilient inner and outer 95 portions projecting from opposite sides of the hub portion and adapted to bear respectively on the head 15 (or the facing portion 15^a thereof), and on the friction disk 31, at the outer marginal portions of said head and disk, the arrangement being such that the resilient portions act conjointly and equally in retarding rotation of the bobbin and in forcing the bobbin toward the mouth 100 of the bobbin case.

In the preferred embodiment shown by Figures 1 to 5 inclusive, the adjunct includes a floating flat sided hub portion 33, preferably of thin sheet steel, an inner series of radial fingers 34 integral with the hub portion 110

and inclined from one side thereof to bear on the case head, and an outer series of resilient radial fingers 35 integral with the hub portion, alternating with the fingers 34, and inclined from the opposite side thereof of the hub portion to bear on the friction disk 31. Said fingers collectively form resilient inner and outer adjunct portions adapted to act conjointly and equally in retarding rotation 10 of the bobbin, the free ends of the fingers being substantially equidistant from the axial center of the adjunct, so that the drag or resistance caused by each series of fingers is practically equal to that caused by the other 15 series. The fingers also act conjointly in forcing the bobbin outward from the case, so that they are adapted, when the case is removed from the shuttle body, to impart a maximum projection to the outer end of the 20 bobbin and thus permit the convenient grasping of said end in removing the bobbin from the tubular post. The radial arrangement of the fingers permits the inward springing thereof until they are in the same plane with 25 the hub portion, so that the adjunct may be compressed to substantially the thickness of the hub portion. Provision is thus made for the cooperation of the adjunct with bobbins of various lengths and having a wide range 30 of difference in length.

Figure 6 shows an adjunct made of sheet metal and including a hub portion 33^a of larger diameter than the hub portion 33, inner fingers 34^a partially cut from the hub 35 portion within the outer margin of the latter and projecting from one side of the hub portion, and similarly formed outer fingers 35^a projecting from the opposite side of the hub portion, and alternating with the fingers 34^a. 40 In my copending application, filed December 3, 1923, Serial No. 678,159, I disclose a bobbin-controlling adjunct interposed between two faces in a bobbin-receiving cavity, a member of said adjunct being composed of 45 an annular flat-sided pressing disk having an extended area of contact with one of said faces, and a plurality of resilient fingers or tongues, integral with the disk and inclined from one side thereof to bear on the other of 50 said faces. The drag or frictional resistance developed by the contact of the flat side of said pressing disk with the face on which it bears, is greater than that developed by the contact of the free ends of the fingers or 55 tongues with the other face, so that when the bobbin thread is relatively small or fine, there is not the desired delicacy of drag or opposition to rotation of the bobbin.

It will be seen that in the use of the improved adjunct involved in this application, 60 the drag or frictional resistance developed

by the contact of the outer resilient fingers with the head, is exactly equal to that developed by the contact of the inner resilient fingers with the disk 31, so that the drag or opposition to the rotation of the bobbin has a degree of delicacy which is desirable under certain conditions. The rotation-retarding effect of the improved adjunct is due wholly to the sliding contact of the fingers with the head and disk, these being the only parts of the adjunct which contact with the head and disk. The fingers are simultaneously tensioned by the bobbin when the shuttle is in use, and their free ends are so spaced from 70 the post that they contact with zones of the head and disk relatively near the outer margins thereof, so that their pressure is distributed and applied to prevent the tipping of the bobbin on the post, when, as often 75 happens, the bobbin core is somewhat loose on the post.

I claim:

In combination, a shuttle comprising a head forming one end of a bobbin-receiving cavity; a central post in said cavity, on which a bobbin in the cavity is rotatable; a thrust support for the bobbin at the opposite end of the cavity, the inner face of said head and an end face of the bobbin being spaced 80 apart within the cavity when the bobbin bears on the thrust support; a friction disk adapted to bear on the inner end of the bobbin; a facing for the face of the head opposite the friction disk; and an annular bobbin-controlling adjunct interposed between said head facing and disk, and composed of an annular floating hub of thin sheet metal, adapted to turn and move sidewise on the post, and two series of resilient fingers 85 integral with the hub, inclined in opposite directions from the sides thereof, and having free ends arranged in two circular series in sliding contact with zones of the head facing and disk, said fingers constituting the only 90 parts of the adjunct which contact with the head and disk, so that the rotation-retarding effect of the adjunct on the bobbin is due wholly to the sliding contact of the fingers with the head and disk, each series of fingers 95 exerting a drag equal to that exerted by the other series, the fingers being simultaneously tensioned by the bobbin when the shuttle is in use, and their free ends being so spaced from the post that they contact with zones 100 of the head facing and disk relatively near the outer margins thereof, whereby tipping of the bobbin on the post is prevented.

In testimony whereof I have affixed my signature.

LUCIUS E. WEAVER,
